CLAIM

The ornamental design for a chair, as shown and described.

DESCRIPTION

FIG. 1 is a front perspective view of a chair; FIG. 2 is a front view of the chair of FIG. 1; FIG. 3 is a rear view of the chair of FIG. 1; FIG. 4 is a left side of the chair of FIG. 1, the right side view being a mirror image of the left side view; FIG. 5 is a top plan view of the chair of FIG. 1; and, FIG. 6 is a bottom plan view of the chair of FIG. 1. The broken lines shown in the drawings are for illustrative purposes only and form no part of the claimed design.

1 Claim, 6 Drawing Sheets
